UNITED STATES PATENT OFFICE.

JAMES BRYANT WHITMORE AND JOHN EBLING FERGUSON, OF BLOOMFIELD, NEW JERSEY, ASSIGNORS TO WESTINGHOUSE LAMP COMPANY, A CORPORATION OF PENNSYLVANIA.

FILAMENT CLAMPER.

Application filed September 8, 1921. Serial No. 498,433.

To all whom it may concern:

Be it known that we, JAMES BRYANT WHITMORE, a citizen of the United States, and a resident of Bloomfield, in the county 5 of Essex and State of New Jersey, and JOHN EBLING FERGUSON, a citizen of the United States, and a resident of Bloomfield, in the county of Essex and State of New Jersey, have invented a new and useful Improvement in Filament Clamps, of which the following is a specification.

This invention relates to devices for clamping one section of a wire to another and it more particularly relates to mechanism for securing the filaments to the leading-in wires in the manufacture of incandescent electric lamps.

An object of the invention is to provide a device for compressing the ends of two wires together and in which the degree of compression employed may be controlled and varied as desired.

Another object is the provision of such mechanism whereby the degree of compression imparted to a wire will be uniform and independent of the operator.

A still further object is to provide means for shearing the end of a compressed wire and subsequently securing the sheared end 30 for the convenience of removal by an operator.

The present invention has proved to be highly advantageous when employed to clamp the ends of leading-in wires about the 35 ends of filaments to complete the lamp mount. Preferably, the ends of the leading-in wires, which are to be connected to the filament, are provided with flattened portions bent to form loops. Thus, in order to clamp 40 a leading-in wire to a filament, the operator positions the filament within the loops of the leading-in wire and then places the wires between a pair of clamping jaws, after which mechanism is actuated to close the jaws to 45 compress the looped end about the filament wire.

The operation of clamping a leading-in wire to a filament is of a delicate character and, unless the clamping is performed with 50 the exact degree of pressure, determined in accordance with practical conditions, depending, for instance, upon the gage and composition of the wire employed, either the

filament or the leading-in wire will be ruptured and, consequently, weakened. It is obvious that, when the operation of a machine depends upon the skill of an operator, a great variation in the pressures results, some wires being subjected to excessive compression and others to an insufficient compression. Leading-in wires have been clamped to filaments by mechanisms of various forms, in which the degree of impact or pressure exerted upon the wires was a variable quantity, being dependent upon the skill and also 55 upon the physical capacity of the operator.

The above disadvantages, common to machines heretofore employed to clamp leading-in wires to filaments, are avoided by the present invention which provides mechanism 60 whereby the blow delivered to clamp the wires is entirely mechanical, independent of the operator, and may be readily adjusted to effect a uniform impact upon the work. The operator is, therefore, free from the mental strain accompanied by an endeavor to 65 impart the necessary degree of pressure upon the wires, and the possibility of a poor union is eliminated.

The invention will be more fully understood by reference to the drawings in which:

Fig. 1 is an enlarged view, in perspective, of the device showing the clamping jaws in their open position;

Fig. 2 is a perspective view showing the 85 relative positions of a leading-in wire and a filament prior to clamping, and Fig. 3 is a similar view showing the leading-in wire clamped to the filament;

Fig. 4 is a view, in perspective, of the 90 clamping device, parts being broken away to more clearly illustrate certain operative parts;

Fig. 5 is a detail perspective view showing the 95 different relative positions of some of the parts of the tripping mechanism; and

Fig. 6 is a detail view of the wire-gripping member.

The embodiment of the invention illustrated in the accompanying drawings comprises a pair of clamping jaws, one of which is carried upon an arm of a crank pivoted to an upright or bracket. The other jaw is fixed and suitably positioned to afford an opposing surface for the movable jaw. The 100 opposite arm of the crank is connected to a 105

reciprocable pull-rod, one end of which is connected to a treadle. This pull-rod is provided with a transverse pin, termed herein the trigger pin, and the pull-rod is held in 5 a normally given position by the engagement of the trigger pin with a latch or trigger. Below the trigger pin and slidable upon the rod, is a casing which provides an intermediate connection between the treadle and 10 the movable jaw, through the agency of an interposed helical spring positioned between a nut or shoulder at one end of the reciprocable rod and the upper portion of the casing. The spring and the other co-operating 15 machine parts will be hereinafter termed a compression member or compression element. The treadle operates the movable jaw under the action of the interposed spring and, as the treadle is moved, the spring is compressed 20 until certain operative parts function to release it and permit the pull-rod and the jaw connected thereto to fly downwardly under the recovery or expansion of the spring. By this means, a given blow is 25 imparted to the rigid jaw or object placed thereon, and the degree of impact of this blow may be quickly and conveniently varied by the adjustment of suitable lock nuts at the end of the rod connected to the movable 30 jaw.

For the purpose of severing a wire after it has been compressed between the clamping jaws, a cutting member is provided in operative relation to the rigid clamping jaw 35 which is actuated by an independent foot treadle and is adapted to shear the wire between its edge and the edge of the rigid clamping jaw. By this means, the wire may be sheared at a point sufficiently near to the 40 clamped wire to meet practical and economical requirements. For the purpose of facilitating the handling of the wire after the cutting off operation has been performed, a slidable opposing gripping member 45 is so positioned as to cause the severed end of the wire to be gripped between the flat end of the cutting jaw and the said gripping member. Thus, an operator may readily pick up the end of the wire for a 50 repetition of the clamping and severing operations.

The general arrangement of the machine illustrated as an example of the present invention will be understood by reference to the drawings and consists essentially of a 55 pair of bell-crank levers 8 and 9 mounted to oscillate on a pivot 10 which has its bearing in a bracket 11 provided with a base 12 adapted to be secured to any suitable bench or table.

A leading-in wire is compressed about a filament by means of a pair of clamps which include a stationary jaw 13 rigidly secured to the bracket 11, and a movable jaw 60 14 removably attached to the smaller arm

of the crank 9. A movement of the crank tends to bring the face of the jaw 14 into contact with the jaw 13 to compress any object positioned therebetween.

Adjacent the clamping jaws is positioned 70 a movable cutting jaw 15 secured to the smaller arm of the crank 8. During a portion of the movement of this cutting jaw, it is adapted to be moved contiguously to the fixed clamping jaw, thus the work, when held between the clamping jaws and projecting therefrom in the direction of the cutting jaw, is sheared by a movement of the cutting jaw as the edge of said jaw passes the edge 75 of the fixed clamping jaw. 80

An object thus sheared would obviously fall and necessitate a certain expenditure of time and exertion on the part of the operator to secure it for further manipulation. In the present machine, provision is made for securing the loose end of a severed object, which provision comprises a suitably disposed resiliently opposed gripping member 16. This member is positioned in the path 85 of movement of the cutting jaw 15 and is normally set to make contact with the cutting jaw, slightly in advance of the cutting operation. The object to be severed is, therefore, secured between the face of the cutting jaw and the gripping member 16, previous 90 to the cutting operation. 95

This gripping member is provided with a shank 18 (see Fig. 6) adapted to slide in a groove 19 in a block 21 secured to the bracket 11. A cover plate 22 is secured to 100 the block 21 and is also provided with a lug 23 which projects downwardly into the groove 19 and above the shank of the member 16. A spring 24, disposed between the lug 23 and the vertical surface 25 of the member 16, normally maintains this member in a position slightly nearer to the jaws 14 and 15 than is the clamping jaw 13, and a set screw 26 serves as a means of varying the normal position of the said member. 110

By means of the gripping member 16, the filament or other object is secured prior to the shearing operation and may be so held until the operator chooses to release it. 115

It is important, in the operation of clamping, to deliver a sharp uniform blow upon the work, and means for accomplishing this may comprise a foot treadle 27 (as shown in Fig. 4) having connections with the bell crank 9. In machines which depend upon an operator to exert a uniform pressure upon a treadle with each clamping operation, the required uniformity is unattainable, it being evident that, as an operator becomes fatigued, the degree of impact upon the work 120 will be decreased. 125

This invention, therefore, provides means whereby the operator merely depresses the treadle to actuate mechanism which will deliver the required uniform blow upon the 130

work. The treadle 27 is connected to a casing 28 through which a pull-rod 29 passes. The upper end of the rod is provided with a transverse slot 31 in which a pin 32 is disposed to secure the rod to the crank 9, the ends of the pin 32 being secured from movement transversely of the slot 31. The pull-rod 29 is slideable in a bearing 33 integral with the base 12 of the bracket. The lower end of the pull-rod 29 is provided with adjusting nuts 34, and positioned between these nuts and the upper side or top of the casing 28 is a helical spring 35. The adjusting nuts 34 are screwed along the rod 29 to bring the spring 35 to a bearing at both ends but without subjecting it to any initial compression. The casing 28 is connected to the treadle 27 by a rod 36 and a pair of links 37. The treadle arm 38 may be hinged on any suitable frame-work 39, and its downward movement may be limited by a nut 41 on the lower end of a depending rod 42 which extends through an aperture in the arm 38 of the treadle.

25 The jaw 14, carried on the crank 9, is maintained in an open position through the action of a spring 43 disposed between a shoulder 44, near the upper end of the pull-rod 29, and the upper end of the bearing 33. The pull-rod is normally maintained in an upper position by the engagement of a pin 45 with triggers 46 disposed at opposite sides of the rod and pivoted in depending projections 47 integral with the base 12. The triggers are of crank shape and engage with the pin 45 by virtue of notches on the lower ends of arms 48. The other arms 49 of the triggers project substantially at right angles to the lower arms and are connected by springs 50 to posts 51 secured to the bearing 33. The springs 50 act to tensionally maintain the engagement of the triggers with the pin 45.

25 The casing 28 is provided with an off-set portion 52 in which a trip rod 53 is secured by nuts 54 and 55. The upper end of the trip rod extends between the arms 49 of the triggers and is provided with studs 56 oppositely disposed and adapted to make contact with the triggers when the trip rod is moved downwardly to release the pin 45 from engagement with the notches disposed in the lower arms of the triggers. The trip rod may be adjusted with respect to the triggers by changing the positions of the nuts 54 and 55 and by a manipulation of a set screw 57; thus, the triggers may be set to be actuated to release the rod 29 while other operating parts are in any given position.

30 The cutting jaw is operated by an independent treadle 58 the downward movement of which is limited similarly to that of the treadle 27 and is carried on the arm 59 hinged on the frame 39. Connection between the arm 59 and the crank 8 is pro-

vided by a rod 60 which is attached to the crank by a pin 61. A spring 62, positioned between the under side of the long arm of the crank 8 and a shelf 63 on the bracket 11, serves to maintain the cutting jaw in an open position. A pin 64, which extends from both sides of a portion of the bracket 11, acts to limit the upward movement of the cranks 8 and 9 and thus regulates the gap between the clamping jaws and the cutter when in normal position.

In practice, the operator positions the filament wire 65 in the loop of a leading-in wire 66, as shown in Fig. 2. Wires so positioned are inserted between the jaws 13 and 14 of the clamping machine. The treadle 27 is then depressed, causing the casing 28 to compress the spring 35 against the nut 34, the rod 29 being temporarily retained from movement by the triggers 46. When the casing is moved a given distance downwardly and compresses the spring 35 to store a sufficient amount of energy, the studs 56 of the trip rod 53 are moved into engagement with the arms 49 of the triggers, and the triggers are disengaged from the rod 29 to permit it to move downwardly, rock the crank 9 and consequently deliver a blow upon the work of such force as may be predetermined and governed by the adjustment of the nuts 34 on the end of the rod 29. The operator may then, without releasing the treadle 27, depress the treadle 58, thereby causing an actuation of the crank 8 and a movement of the cutting jaw 15 which moves and secures an end 67 of the filament in contact with the face 68 of the resilient member 16, and a continued movement of the jaw 15 severs the end 67 and also retains it in a convenient position for removal by the operator, who then releases both treadles, permitting the jaw 14 to open under the action of the spring 43 which also serves to move the rod 29 upwardly until the trigger is again engaged with the pin 45, thereby setting the operative parts of the device for the next clamping operation. The cutting jaw returns to its normal open position through the action of the spring 62.

It will be understood that an exceedingly fine variation in the degree of blow delivered may be had with this device. By an adjustment of the nuts 41, which limit the downward movement of the treadle, and a rearrangement of the trip rod 53 and the nuts 34, a greater or lesser degree of compression may be imparted to the spring 53 and thus the potential energy required may be varied in accordance with the required impact desired for different sizes of wire or variation in the properties of material used.

It will be understood that the particular construction and arrangement of parts herein shown may be greatly varied, and many changes will suggest themselves to those

skilled in the art, all of which come within the spirit of our invention, in so far as they fall within the scope of the annexed claims.

What is claimed is:

5. 1. A machine for securing incandescent lamp filaments to leading-in wires, comprising a pair of jaws and means for causing an impact of a predetermined pressure between said jaws. 70
10. 2. A machine for securing incandescent lamp filaments to leading-in wires, comprising a pair of jaws and means for causing an impact of predetermined force upon a wire interposed therebetween and means for severing said wire. 75
15. 3. A machine for securing incandescent lamp filaments to leading-in wires, comprising a pair of jaws, means for causing an impact of a predetermined force between said jaws and means for varying the degree of impact. 80
20. 4. A machine for securing incandescent lamp filaments to leading-in wires, comprising a fixed jaw, a movable jaw and means for actuating said movable jaw to effect an impact of a predetermined force upon the fixed jaw. 85
25. 5. A machine for securing incandescent lamp filaments to leading-in wires, comprising a fixed jaw and a movable jaw, means for actuating said movable jaw to cause an impact upon said fixed jaw and means for varying the degree of said impact. 90
30. 6. A machine for securing incandescent lamp filaments to leading-in wires, comprising a fixed jaw and a movable jaw, means for actuating said movable jaw to effect an impact upon a wire interposed between said jaws and means for severing said wire. 95
35. 7. A machine for securing incandescent lamp filaments to leading-in wires, comprising a fixed jaw and a movable jaw, means for actuating said movable jaw to cause an impact upon a wire interposed between said jaws, means for varying the degree of said impact and means for severing said wire. 100
40. 8. A machine for securing incandescent lamp filaments to leading-in wires comprising a pair of clamping jaws and a cutting jaw, means for actuating the clamping jaws to cause a given impact upon a wire positioned therebetween and means for actuating the said cutting jaw to sever said wire. 105
45. 9. A machine for securing incandescent lamp filaments to leading-in wires, comprising a pair of clamping jaws and a cutting jaw, means for actuating the clamping jaws to produce a given impact upon a wire positioned therebetween, means for varying the degree of said impact and means for actuating the cutting jaw to sever said wire. 110
50. 10. A machine for securing incandescent lamp filaments to leading-in wires, comprising a pair of clamping jaws, means for normally retaining said jaws in an open position, means for storing energy in operative relation to said jaws and means for delivering said energy to cause an impact between said jaws. 115
55. 11. A machine for securing incandescent lamp filaments to leading-in wires, comprising a pair of clamping jaws, means for retaining said jaws in an open position, means for accumulating energy in operative association with said jaws, means for varying the amount of said energy and means for utilizing said energy to operate said jaws and cause an impact therebetween. 120
60. 12. A machine for securing incandescent lamp filaments to leading-in wires, comprising a rigid jaw and a movable jaw, means for retaining said movable jaw in an open position, means for accumulating energy in operative relation to said movable jaw and means for utilizing said energy to cause an impact between said jaws. 125
65. 13. A machine for securing incandescent lamp filaments to leading-in wires comprising a rigid jaw and a movable jaw, means for retaining said movable jaw in an open position, means for accumulating energy in operative association with said movable jaw, means for varying the amount of energy accumulated and means for expending said energy to actuate said movable jaw and produce an impact upon said rigid jaw. 130
70. 14. A machine for securing incandescent lamp filaments to leading-in wires comprising a pair of clamping jaws having a compression member associated therewith, means for compressing and normally retaining said member under compression and means for releasing said member whereby a rapid closure of said jaws is effected. 135
75. 15. A machine for securing incandescent lamp filaments to leading-in wires comprising a pair of clamping jaws having a compression member associated therewith, means for compressing and temporarily maintaining said member under compression and means for suddenly releasing said compression member to cause an impact between said jaws. 140
80. 16. A machine for securing incandescent lamp filaments to leading-in wires comprising a pair of clamping jaws having a compression member associated therewith, means for compressing and normally retaining said member under compression, means for varying the degree of compression and means for releasing said member whereby a rapid closure of said jaws is effected. 145
85. 17. A machine for securing incandescent lamp filaments to leading-in wires comprising a rigid jaw and a movable jaw, a compression element, means for compressing said element when said movable jaw is in an open position and means for releasing said element to effect an impact between said jaws. 150
90. 18. A machine for securing incandescent

- lamp filaments to leading-in wires comprising a rigid jaw and a movable jaw, a resilient member, means for compressing said member when said movable jaw is in an open position, means for varying the degree of compression of said member and means for permitting the expansion of said member to cause an impact between said jaws.
- 10 19. A machine for securing incandescent lamp filaments to leading-in wires comprising a rigid jaw and a movable jaw, a compression member, means for compressing said member when said movable jaw is in an open position, means for releasing said member to effect an impact between said jaws and means for automatically returning said jaws to a normally open position.
- 20 20. A machine for securing incandescent lamp filaments to leading-in wires comprising a rigid jaw and a movable jaw, a compression member, means for compressing said member when said movable jaw is in an open position, means for varying the degree of compression of said member, means for releasing said member to cause an impact between said jaws and means for automatically returning said jaws to an open position.
- 25 21. A machine for securing incandescent lamp filaments to leading-in wires comprising a pair of clamping jaws, a compression element adapted to operate said clamping jaws, means for temporarily maintaining said element at a predetermined degree of compression, and means for effecting a sudden expansion of said element whereby said clamping jaws are caused to close upon and compress a wire positioned therebetween.
- 30 22. A machine for securing incandescent lamp filaments to leading-in wires comprising a pair of clamping jaws and a cutting jaw disposed in operative relation to one of said clamping jaws, means for moving the clamping jaws to compress a wire disposed therebetween and means for operating said cutting jaw to shear said wire.
- 35 23. A machine for securing incandescent lamp filaments to leading-in wires comprising a pair of clamping jaws and cutting jaw disposed in operative relation to one of said clamping jaws, a compression member adapted to operate said clamping jaws, means for temporarily compressing the compression member, means for releasing said member to actuate said jaws and compress a wire positioned therebetween and means for operating said cutting jaw to shear said wire.
- 40 24. A machine for securing incandescent lamp filaments to leading-in wires comprising a pair of clamping jaws and a cutting jaw disposed in operative relation to one of said clamping jaws, means for moving the clamping jaws to compress a wire disposed therebetween, means for operating said cutting
- 45 50 55 60 65 70 75 80 85 90 95 100 105 110 115 120 125 130
- lamp filaments to leading-in wires comprising a rigid jaw and a movable jaw, a resilient member, means for compressing said member when said movable jaw is in an open position, means for varying the degree of compression of said member and means for permitting the expansion of said member to cause an impact between said jaws.
- 70 75 80 85 90 95 100 105 110 115 120 125 130
- lamp filaments to leading-in wires comprising a pair of clamping jaws and a cutting jaw disposed in operative relation to one of said clamping jaws, a compression element adapted to operate said clamping jaws, means for temporarily maintaining said element at a predetermined degree of compression and means for effecting a sudden expansion of said element whereby said clamping jaws are caused to close upon and compress a wire positioned therebetween and means for operating said cutting jaw to shear said wire.
- 75 80 85 90 95 100 105 110 115 120 125 130
- lamp filaments to leading-in wires comprising a pair of clamping jaws, a cutting jaw and a gripping member disposed in operative relation thereto, means for actuating said clamping jaws to compress a wire positioned therebetween and means for operating said cutting jaw to sever said wire and grip the wire between the cutting jaw and said gripping member.
- 80 85 90 95 100 105 110 115 120 125 130
- lamp filaments to leading-in wires comprising a pair of clamping jaws, a cutting jaw and a gripping member disposed in operative relation thereto, a compression element and means associated therewith whereby said clamping jaws are actuated by said element, means for compressing said element, means for releasing said element to cause an impact upon a wire positioned between said jaws and means for operating said cutting jaw to sever said wire and grip one end of the severed portions thereof between the cutting jaw and said gripping member.
- 85 90 95 100 105 110 115 120 125 130
- lamp filaments to leading-in wires comprising a pair of clamping jaws and a cutting jaw, a gripping member disposed in operative relation to said cutting jaw, means for causing an impact of predetermined force between said clamping jaws to compress a wire positioned therebetween and means for actuating the cutting jaw to sever said wire and grip the same between the said cutting jaw and said member.
- 90 95 100 105 110 115 120 125 130
- lamp filaments to leading-in wires comprising a pair of clamping jaws, a cutting jaw, a gripping member disposed in operative relation to said cutting jaw, means for causing an impact of predetermined force between said clamping jaws to compress a wire positioned therebetween, means for actuating the cutting jaw to sever said wire and grip the same between the said cutting jaw and said member and means for moving said cutting jaw to release said wire.

30. A machine for securing incandescent lamp filaments to leading-in wires comprising a pair of clamping jaws, a cutting jaw, a resiliently opposed gripping member disposed in operative relation to said cutting jaw, means for actuating said clamping jaws to compress a wire a predetermined amount and means for operating said cutting jaw to sever said wire and secure it between the end of said cutting jaw and the opposing face of said gripping member.
31. In a machine for securing filaments to leading-in wires, the combination with a stationary jaw and a movable jaw having an arm integral therewith, a pull-rod pivotally connected to said arm, a casing movable upon said rod, a resilient member disposed in engagement with said casing and said rod, a trigger adapted to retain said rod normally in a given position, a trip rod positioned to engage said trigger and release the said rod when the relative positions of the casing and rod are changed and the resilient member is compressed.
32. In a machine for securing filaments to leading-in wires, the combination with a stationary jaw, a movable jaw having an arm integral therewith, a pull-rod pivotally connected to said arm, a casing movable upon said pull-rod, a resilient member disposed in engagement with said casing and said pull-rod, a treadle pivotally connected to said casing, a trigger adapted to retain said pull-rod in a given initial position in opposition to said resilient member, whereby a depression of the treadle causes a compression of said resilient member between said pull-rod and casing, a trip-rod secured to and movable with said casing and so positioned as to release said pull-rod from engagement with said trigger when the treadle has been moved a given distance.
33. In a machine for securing filaments to leading-in wires, the combination with a pair of clamping jaws comprising a stationary jaw and a movable jaw having an arm integral thereto, a movable cutting jaw disposed adjacent to said clamping jaws and having an arm integral therewith, a connecting rod pivotally connected to the arm of said cutting jaw and to a treadle, a gripping member positioned in operative relation to said cutting jaw, a depending pull-rod pivoted to the arm of said movable clamping jaw, a casing movable upon said pull-rod, a helical spring disposed between a shoulder on said pull-rod and one end of said casing, a trigger adapted to maintain said rod in a given normal position, a trip-rod attached to said casing, a connection between said casing and a treadle whereby an initial movement of said treadle causes a movement of said casing and a compression of said spring and a further movement of said treadle causes the trip-rod to release said pull-rod to effect an impact between said clamping jaws.

In testimony whereof, we have hereunto subscribed our names this second day of September 1921.

JAMES BRYANT WHITMORE.
JOHN EBLING FERGUSON.
